ROTARY PUMP

Hanley T. Woo, Seattle, Wash.

Application October 2, 1929. Serial No. 396,813

1 Claim. (Cl. 103—140)

My invention relates to rotary pumps and the object of my invention is to provide a rotary pump which is self-priming, highly efficient in operation, which has a very large capacity in proportion to the size of the machine, which is simple and cheap in construction, which has few moving parts and will run without vibration, which has means for automatically compensating for wear on the vanes and which will not be seriously affected by grit, sand and dirt in the liquid.

Another object is to provide a pump of this nature having a cylindrical rotor eccentrically disposed within a cylindrical housing of larger size, said rotor having vanes pivotally mounted therein and arranged to follow the walls of the housing as the rotor rotates, the vanes also having resilient means for urging them outwardly and having rollers thereon for rolling on the walls of the cylindrical housing to reduce friction and wear between the vanes and the housing.

Another object is to provide means, in the nature of passageways in the rotors, for allowing the liquid pressure on the discharge side of the pump to enter behind the vanes on the suction side and help to hold said vanes out against the wall of the housing during the time they are moving outwardly.

Other and more specific objects will be apparent from the following description taken in connection with the accompanying drawings.

Rotary pumps are usually provided with vanes which wear against the internal wall of a housing in which they are enclosed. When these pumps are used for pumping water containing sand and grit they wear and cut very rapidly. This soon causes leakage past the vanes which greatly reduces the efficiency of said pumps and finally renders the pumps totally inoperative. In accordance with my invention I provide rollers on the vanes arranged to roll on the inner walls of the housing and prevent undue friction and cutting between the walls of the housing and the vanes, said rollers being large enough to roll over sand and grit without substantial wear.

The above mentioned general objects of my invention, together with others inherent in the some are attained by the mechanism illustrated in the following drawings, the same being a preferred exemplary form of embodiment of my invention, throughout which drawings like reference numerals indicate like parts:

Figure 1 is an elevation, with a side wall of

the housing removed, of a rotary pump constructed in accordance with my invention;

Fig. 2 is a vertical cross section of the same substantially on a broken line 2—2 of Fig. 3;

Fig. 3 is a vertical cross section substantially on 60 a broken line 3—3 of Fig. 2;

Fig. 4 is a detached elevation of one of the vanes with one roller removed and the other roller on the vane; and

Fig. 5 is an elevation of the vane shown in 65 Fig. 4.

Referring to the drawings, 6 designates a main housing member provided with a cylindrical inner wall 7 and having oppositely disposed intake and discharge ports 8 and 9 respectively. The 70 housing member 6 is provided with a base 10 and has two end plates 11 and 12 secured thereto by cap screws 13. A bearing 14 having a closed end may be provided on the end plate 11 and a stuffing box 15 may be provided in the other end 75 plate 12 for preventing leakage around a main shaft 16. A separate bearing bracket 17 is secured to the end plate 12 and extends outwardly beyond the stuffing box 15 to form a bearing for this end of the shaft 16. A drain cock 18 may be 80 provided in one of the side plates, as in the plate 11, near the bottom of the pump.

The shaft 16 is eccentric relative to the housing 6 and carries a rotor which is eccentrically disposed within said housing. The rotor comprises 85 a main rotor member 19, of generally cylindrical shape, having a hub portion 20 secured to the shaft 16 by a key 21 and having diametrically opposite notches 22 and 23 for the reception of vanes 24 and 25 respectively. The shaft 16 is 90 concentric relative to the rotor and eccentric relative to the housing so that the rotor is held in contact with the housing wall at a point between the intake 8 and discharge 9 and leaves a crescent shaped passageway extending from 95 one side of this contact point or area around the major portion of the rotor and housing to the other side of said contact point or area. Side plates 26 and 27 are rigidly secured to the sides of the rotor, as by screws 28. These side plates 100 have diametrically opposite recesses 29 and 30 positioned over the rotor notches 23 and 22 and adapted to receive rollers 31, as shown in Fig. 1. The rollers 31 are mounted on bearing pins 32 which extend rotatably through the vanes 24 105 and 25 so that said rollers are allowed to move inwardly and outwardly within the recesses 29 and 30 as the vanes move within the notches 22 and 23. The rollers 31 are positioned so that they roll on the cylindrical walls 7 of the housing 110.

and relieve the vanes of frictional contact and wear as the rotor rotates.

The rear ends of the vanes 24 and 25 are seated within the rear ends of the notches 22 and 23 5 and are mounted on pivot pins 33 which extend outwardly through the side plates 26 and 27. The front ends of the vanes are curved arcuately from centers of curvature located at the centers of the pivot pins 33 and the front walls 34 of 10 the notches 22 and 23 are similarly curved to allow the vanes to move inwardly and outwardly without drawing away from said walls. The outer surfaces of the vanes are curved from the rear to a point near the forward end, preferably 15 on the same radius as the rotor, and have their front ends curved off more sharply as at 34' to fit the wall 7 when the vanes are in the outermost position in which the lower vane 25 is shown in Fig. 1. The vanes are preferably cored 20 out on their inner sides as shown in Fig. 2, thereby affording a storage space for liquid, and are suitably shaped to conform to the curvature of the bottoms of the notches 22 and 23. Two slidably mounted pins 35 and 36 extend diametrical- 25 ly through the rotor hub 20 and shaft 16 and press outwardly against the vanes 24 and 25 to assist in holding said vanes in contact with the walls 7 of the housing. A compression spring 37 is interposed between the two pins 35 and 36. The 30 vanes 24 and 25 are also urged outwardly by centrifugal force due to the rotation of the rotor. Said vanes are further urged outwardly by fluid pressure as follows: The rotor 19 is cored out between the vanes leaving cavities 38 and these 35 cavities 38 are connected with the notches 22 and 23 by passageways 39, see Fig. 2. When the vanes are in the position shown in Fig. 1 most of the liquid under the uppermost vane 24 will be squeezed out and will fill the notch 23 under 40 the vane 25. As the rotor moves on around in a counter clockwise direction toward the position shown in Fig. 2 the vane 25 will be moved inwardly, squeezing out the liquid from the notch 23 and forcing it into the notch 22 back of the vane 24 thus tending to force the vane 24 outwardly. This relieves excess pressure back of the inwardly moving vane and creates a desired 45 pressure back of the outwardly moving vane. This pressure is also communicated to the recesses 29 and 30 back of the rollers 31. 50

The wall of the housing 6 at the lower edge of the inlet port 8 is cut away as at 40 to avoid constriction at this point and afford a larger intake opening.

55 In the operation of this pump when the rotor is driven in a counter clockwise direction as indicated by the arrows in Figs. 1 and 2 water will be drawn in behind each vane as it passes the intake port and moves on around the housing and this 60 water will be picked up by the next succeeding vane and expelled through the discharge port 9. The velocity of the water is substantially constant from the time it enters the pump until it leaves

the same and there are no abrupt changes in the direction of flow of the water. This is conducive to high efficiency and to the elimination of vibration in the pump.

The recesses 38 retain the liquid so that upon 80 restarting the pump after remaining idle the pump embodying my invention has self-contained water ready to effect a seal and thereby eliminate all necessity of priming, a most important even necessary feature when a pump of this type is 85 employed in pumping lubricating oil for an internal combustion motor or fuel oil for an oil burner apparatus.

The bottom of the inlet port and the bottom 90 of the outlet port must be in applicant's device at least 180 degrees apart where he employs two vanes spaced 180 degrees apart. This avoids loss of efficiency by the complete separation at all times between the high pressure outlet and the low pressure inlet.

The rollers 31 rolling on the wall 7 of the housing support the vanes against radial thrust and prevent excessive wear and friction between the vanes and the housing wall and tend to prevent rapid wear where water containing sand and grit 100 is being pumped.

Obviously, changes may be made in the form, dimensions and arrangement of the parts of my invention, without departing from the principle thereof, the above setting forth only a preferred 105 form of embodiment.

I claim:

A rotary pump embodying a cylindrical housing; a rotor eccentrically mounted for rotation within said housing; means forming an intake port and a discharge port, said ports being disposed substantially at or above the horizontal plane through the center of the rotor, said rotor being tangential to the walls of said housing, substantially midway between said ports, said intake port having a cutaway portion at its lower edge extending downwardly therefrom, communicating with the interior of said housing, and affording an enlarged intake opening, said rotor having two diametrically opposite notches in its 110 periphery; two pumping vanes operatively mounted in said notches, said pumping vanes having internal cavities for storage space in communication with said notches; two relatively large cored cavities in sectors of the body of the rotor, 115 said cavities extending substantially all of the distance between the respective notches and substantially from the center to the circumference of the rotor; relatively restricted passageways positioned substantially adjacent the central wall 120 of the cavities and establishing communication through said relatively restricted passageways between each cavity and each notch, whereby a substantial storage space for fluid is provided within the rotor and the vanes, so that a sub- 125 stantial supply of fluid for priming purposes upon restarting the pump is available.
